UNITED STATES PATENT OFFICE.

ALEXANDER R. FORDYCE, OF NEWARK, NEW JERSEY.

METALLIC LATHING.

SPECIFICATION forming part of Letters Patent No. 557,658, dated April 7, 1896.

Application filed November 16, 1895. Serial No. 569,221. (No model.)

To all whom it may concern:

Be it known that I, ALEXANDER R. FORDYCE, a citizen of the United States, residing at Newark, in the county of Essex and State of New Jersey, have invented certain new and useful Improvements in Metallic Lathing, of which the following is a full, clear, and exact description, such as will enable those skilled in the art to which it appertains to make and use the same, reference being had to the accompanying drawings, which form a part of this specification.

The invention relates to improvements in metallic skeletons of that class which are adapted to be used in the construction of fire-proof walls, ceilings, partitions, &c.

It relates more particularly to that class of skeletons which is termed "metallic lathing," which, when attached to suitable supports, forms the foundation for the filling that goes to make the body of such constructions.

It relates especially to improvements in that kind of lathing that is made by providing sheet metal with rows of slots, which break joint, and then expanding the metal so treated. In lathings of this sort as heretofore made in order to give them the desired strength it is necessary to use sheet metal of considerable thickness or to use numerous auxiliary supports. When metal of considerable thickness is used, owing to its consequent stiffness and want of pliability, much trouble is experienced in cutting and forming the lathing. The use of numerous auxiliary supports is also objectionable, especially in the construction of thin walls, as the contiguity of the filling is considerably interrupted, and, furthermore, the use of the thick metal and the numerous supports greatly increases the weight of the structure; also, in walls of considerable thickness these lathings do not form a sufficient skeleton. The outstanding keys or projections are so shallow that to a considerable depth the filling of such walls is unsupported. This is a serious disadvantage, especially when the filling is in a green state, as it would be very liable to displacement.

In the invention in the present instance it is proposed to overcome these objections to a considerable extent. It consists, primarily, in corrugating the metal at right angles to the general direction taken by the slits. In this

way a lathing is formed which will be considerably stronger than the plane lathing or that corrugated parallel with the direction taken by the perforations, which will allow the use of comparatively thin sheet metal and of fewer auxiliary supports; also, a skeleton can be constructed which will have considerable depth or thickness, which renders it especially applicable to the construction of thick walls, and, furthermore, the engaging edges of the keys will be greatly lengthened, and thereby a more thorough bonding of the filling will be insured.

The invention further consists in the novel construction and arrangement of parts, such as will be hereinafter fully described, pointed out in the appended claims, and illustrated in the accompanying drawings.

In the accompanying drawings, in which similar letters of reference designate corresponding parts, Figure 1 is a plan view of a piece of metallic lathing embodying the invention. Fig. 2 is a similar view showing a sheet of metal after it has been slitted and corrugated, but before it has been expanded. Fig. 3 is a section on the line 3 3 of Fig. 2. Fig. 4 is a section on the line 4 4 of Fig. 1. Fig. 5 is a section on the line 5 5 of Fig. 1. Fig. 6 is a perspective view of a section of the lathing. Fig. 7 is a view similar to that shown in Fig. 2, the slits being straight instead of angular. Fig. 8 is a perspective view of a section having straight slits.

In carrying out the invention a metallic plate A of the required dimensions is first provided with rows of parallel angular slots, or straight ones, as shown in Fig. 7, a a, the ends a' a' of which break joint with the ends a' a' of the slots of the adjacent rows. The apexes or angles a² a² of the slits register—that is, they fall one directly beneath the other. After this has been done the plate is corrugated so that the ribs a³ a³ extend at right angles to the general direction taken by the slits. The plate will then have the appearance shown in Fig. 2. The plate is then drawn or expanded, so that the slot will open into uniform geometrical figures of very irregular outlines. Keys a⁴ a⁴, having ribs a⁵ a⁵, will thereby be formed, and the plate will have the general appearance shown in Figs. 1 and 6. The keys so formed will project in

alternate rows from opposite sides of the plate and will be considerably inclined from the main plane of the plate. This excessive inclination is caused by the corrugations, the 5 key itself being made so stiff thereby that it will not bend when the plate is expanded, while on the other hand the comparatively narrow ribs, owing to the comparatively great length of the same, will allow considerable 10 movement of the keys.

While it is preferred to have the slots angular, yet they may be given any other desired form—straight, for an instance—with departing from the spirit of the invention. Of 15 course where the slots are straight the keys will not have so great an inclination as they will when the slots are angular. It is also to be observed that a plate so treated will form ornamental screens and may be used for other 20 decorative purposes.

Having thus described my invention, what I claim, and desire to secure by Letters Patent, is—

1. A lathing consisting of a metallic plate 25 having corrugated keys projecting therefrom, the corrugations extending longitudinally through the said keys, substantially as described.

2. A lathing consisting of a corrugated metallic plate, slitted and expanded, the corrugations extending through the slitted portion 30 of the plate and at right angles to the general

direction taken by the slits, substantially as described.

3. A lathing consisting of a corrugated metallic plate provided with rows of angular slits 35 which break joint, and expanded to throw keys from opposite sides of the plate, substantially as described.

4. A lathing consisting of a metallic plate 40 provided with rows of angular slits, which break joint, and expanded to throw keys from opposite sides of the plate, substantially as described.

5. A lathing consisting of a metallic plate 45 having corrugated keys projecting from the opposite sides thereof and pointing in opposite directions, substantially as described.

6. A lathing consisting of a metallic plate having corrugated keys projecting from the 50 same in alternate rows on opposite sides and pointing in opposite directions, substantially as described.

7. In a metallic lathing, the combination of the corrugated keys and the corrugated ribs 55 connecting the same, substantially as described.

In testimony whereof I hereunto affix my signature in the presence of two witnesses.

ALEX. R. FORDYCE.
